(57) **CLAIM**

The ornamental design for a fitness band with call function, as shown and described.

DESCRIPTION

FIG. 1 is a front elevational view of a fitness band with call function showing my new design;

FIG. 2 is a rear elevational view thereof;

FIG. 3 is an enlarged left side view thereof;

FIG. 4 is an enlarged right side view thereof;

FIG. 5 is a top plan view thereof;

FIG. 6 is a bottom plan view thereof;

FIG. 7 is a perspective view thereof with the wireless headset partially detached from the band;

FIG. 8 is another perspective view of FIG. 7;

FIG. 9 is a perspective view thereof with the band in an unbuckled condition;

FIG. 10 is a perspective view thereof with the wireless headset completely removed from the band;

FIG. 11 is another perspective view of FIG. 10;

FIG. 12 is another perspective view of FIG. 10 with the band in an unbuckled condition;

FIG. 13 is a perspective view of the wireless headset; and,

FIG. 14 is another perspective view of the wireless headset.
